UNITED STATES PATENT OFFICE.

LUTHER E. PHILLIPS, OF BRISTOL, NEW YORK.

IMPROVEMENT IN MACHINES FOR CUTTING TAPERING FORMS.

Specification forming part of Letters Patent No. 42,504, dated April 26, 1864.

To all whom it may concern:

Be it known that I, LUTHER E. PHILLIPS, of Bristol, in the county of Ontario and State of New York, have invented a new and useful Machine for Sharpening Fence-Posts, Fence-Stakes, Hop-Poles, and Piles; and I do hereby declare that the following is a full and exact description thereof, reference being had to the accompanying drawings, and to the letters of reference marked thereon.

The nature of my invention consists in so constructing, adapting, and combining the different parts of the machine that tapering forms can be cut with great ease and rapidity, thus fitting hop-poles, fence-posts, fence-stakes, and piles for use much more cheaply and in a much better manner than it has hitherto been done.

To enable others skilled in the art to make and use my invention, I will proceed to describe its construction and operation.

In the drawings, Figure 1 represents a perspective view of the complete machine. Fig. 2 represents a view of the conical tube attached to its shaft, and to which the cutting-knife is fastened. Fig. 3 is a cross section of Fig. 2 at the intersection of the line *a a*, showing the bar which holds the knife, and also the bar on the opposite side of the conical tube, which, while it balances by its weight the other side, thus allowing it to revolve with great velocity without vibration or jar, is designed (as is also the other bar) to strengthen the tube and render it capable of performing the work intended for it.

In Fig. 1, *A A* is a strong frame. *H* is a carriage or sliding frame on *A*, designed to

support the timber to be cut. *G* is a strong transverse plank securely fastened to the frame, and through which passes the outer end of the conical tube, revolving in a metallic box or bush, *h*, in *G*. *C* is the conical tube, and *B* is the shaft to which it is securely fastened. *D* is a fly-wheel, and *a* is a pulley on the said shaft, which is supported by cross-timbers *b*. The timber to be operated on, *T*, is firmly held to the sliding frame *H* by levers, as seen at *I* and *l*. They are loosely connected at their ends, forming a joint, and with fulcrums for each at *L L*, as seen in the drawings. When the end of the long lever *I* is depressed, it throws down the end of *l* upon the timber, holding it fast. The conical tube *C* and the shaft *B* are of iron, as are the bars. *d d* on the tube *C* is the knife, securely attached to *d* by screw-bolts *fff*, and having slot-holes, which allow it to be moved up or back, as necessity may require.

I do not claim the conical tube for cutting tapering forms as my invention, it having been long known and used; but

What I do claim as my invention, and desire to secure by Letters Patent, is—

The conical tube *C*, when constructed with strengthening and balancing bars *d*, in combination with the arrangement of the feeding-carriage *H* and its holding device, when constructed to operate as and for the purposes substantially as set forth.

LUTHER E. PHILLIPS.
